UNITED STATES PATENT OFFICE.

PATRICK P. LA MONTAGNE, OF BOURBONNAIS, ILLINOIS, ASSIGNOR, BY MESNE ASSIGNMENTS, TO POPE MACHINE COMPANY, OF KANKAKEE, ILLINOIS, A CORPORATION OF ILLINOIS.

KNITTING-MACHINE NEEDLE.

Application filed December 7, 1917. Serial No. 205,981.

To all whom it may concern:

Be it known that I, PATRICK P. LA MONTAGNE,

a citizen of the United States, residing at Bourbonnais, county of Kankakee,

5 State of Illinois, have invented an Improvement in Knitting-Machine Needles, of which the following description, in connection with the accompanying drawing, is a specification, like characters on the drawing representing like parts.

This invention relates to a knitting machine and particularly to the needle. The needle is of the type in which the hook member and latch member are separate members, 15 that is, physically independent and separate from each other although co-acting to perform the required looping functions.

It is the object of the invention to provide a needle of this type in which the needle 20 members shall be projected to forward position with great accuracy, and in which both members of the needle shall be so constructed as to be rapidly, accurately and inexpensively made, and largely by punching or stamping operations.

These and other features and objects of the invention will appear more fully from the accompanying description and drawings and will be particularly pointed out in the 30 claims.

The drawings represent so much of a knitting machine as is necessary to a disclosure of the invention.

In the drawings,

35 Figure 1 is a central vertical cross section of a portion of the dial of an ordinary type of knitting machine with the preferred form of needles embodying the invention in position therein;

40 Fig. 2 is a side elevation of a preferred form of needle with the hook member shown in vertical cross section and with the parts in casting off position;

Fig. 3 is a view similar to Fig. 2 but with 45 the parts shown in forward projected or yarn receiving position;

Fig. 4 is a plan view of a section of the construction shown in Figure 1 with the cams and parts above the needle removed;

50 Fig. 5 is a view in vertical cross section of a portion of a needle cylinder with a needle

embodying the present invention adapted for use therein.

The needle of this invention is of the general type disclosed in the patents to Pope 55 and Randall No. 1,096,946, granted May 19, 1914, and No. 1,241,882, granted October 2, 1917, wherein the needle is composed of two members, a hook member moving in a slot formed in the needle bed and a separate 60 latch member extending through a slot in the hook member and having a movement relative to the hook member to bring the point of the latch into and out of co-operation with the hook, and wherein the latch 65 member projects into and moves in a second slot formed in the needle bed beneath the slot for the hook member. In this type of needle movement is imparted to one of the members, preferably the hook member, by a 70 cam such as the usual cam employed for operating knitting machine needles and a retarding friction is applied to the other member, such as the latch member, preferably by causing it to bind slightly in its slot. 75

The present invention is more particularly concerned with the form of needles used in the dial of a knitting machine because the problems arising from the limitations of space and of restriction of movement are 80 more difficult but the main principles of the invention are equally applicable to the cylinder needle, and both forms are herein illustrated.

It is highly important that the hook and 85 latch members shall be accurately positioned both with respect to each other and with respect to the needle bed in the forward or projected position. The parts of the needle in moving to the forward or projected position must be moved positively and accurately. This accurate positioning and movement is secured in the present invention by providing co-operating shoulders on the shanks of the hook and latch members which are formed 90 by punching or stamping operations thus insuring accuracy of relation between the shoulder on the hook member and the hook and the shoulder on the latch member and the point of the latch. In the manufacture 100 of knitting machine needles the usual slot through the body of the needle or the hook

member is formed by a sawing operation and the shoulders resulting from this sawing operation vary in position and in a series of needles do not occupy exactly the same relation with respect to the hook so that such shoulders produced by such a sawing operation cannot be depended upon when accuracy of needle movement is required.

The difference in accuracy between shoulders formed by a punching or stamping operation in the shanks of the members as herein provided and those formed by a sawing operation is a very substantial one. Accuracy of positioning and movement is of the highest importance especially in connection with the dial needle. The yarn is fed into a very limited space between the end of the latch point and the point of the hook. If the hook and latch members are not accurately placed in yarn receiving position the yarn may not be caught by the hook or may feed onto the latch and be cast off without making a stitch. Furthermore, if the latch be not projected to the proper position the yarn of the preceding stitch may not ride past the point or tip of the latch and as a result would not be cast off upon the retracting movement but would slide under and be caught by the hook. In the case of the dial needles also the yarn is fed to the dial needles by the cylinder needles which pull the yarn down onto the dial needles and must pull it within narrow limits so that accurate positioning of the dial needles is especially important in the yarn receiving position. Furthermore, especially in the finer grades of work the number of dial needles is great and the dimensions small, but it is essential, and even more essential as the number of the dial needles increases and their dimensions decrease, that all of the needles shall be in exactly the same position to insure the casting off of the last stitch and the taking on of the new stitch without casting off.

It will thus be seen that the arrangement of punched or otherwise accurately formed shoulders on the hook and latch members co-operating to secure the proper relative forward or projecting movement and to bring the members accurately into forward, projected or yarn receiving position, is of the greatest importance.

The construction of the members with similar shoulders co-operating on the reverse or retracting movement especially in the case of the dial needles would be difficult if not impossible because such a shoulder in the hook member would leave insufficient area of wall surface of the slot in the hook member through which the latch member projects to afford proper support and guidance for the needle members relatively to each other. Accuracy of co-operation in the retracting movement is not of great impor-

tance because it is only necessary on the reTRACTING movement that the members shall be in such position that the latch point shall cover the tip of the hook and shall insure casting off.

70

The hook member projecting through the slot in the latch member has a movement longitudinally of the hook member and also transversely of the hook member to cause the point of the latch to move into and out of co-operative relation with the tip of the hook. In order that this movement may take place with the minimum amount of wear and friction the guiding surfaces of the two members are herein each given extended straight formation so that during this movement two flat surfaces are for the most time in contact throughout.

The tip of the hook is provided on its outer surface with a small recess or groove to receive the point of the latch when the needle is retracted. As thus arranged the point of the latch is supported at its outer or free end in the recess of the tip of the hook and at its base on the inclined guiding surface so that the heavy strain of the yarn loop is taken up by a bridging action of the latch point.

The provision of the recess in the tip of the hook also enables the total cross section of the needle in the casting off position to be at the minimum because the point of the latch fits into this recess. This is particularly desirable in fine work. This arrangement of the parts also eliminates any space between the overlapping latch point and hook tip through which the yarn may slip back beneath the hook.

In the construction illustrated in Figs. 1 to 4 inclusive dial needles embodying these features of the invention are disclosed.

The bed 1 of a dial supported on the vertical stud or shaft 2 is shown as provided with narrow radial slots 3 to receive the latch members and wider superimposed slots 4 to receive the hook members of the needle. The usual cam 5 is shown with its cam slot for operating the butts of the hook members to give the necessary movement.

In the form of the needle illustrated the hook member is thus positively moved in and out or back and forth by the cam 5 and the latch member receives its movement from the hook member. A retarding action is given to the latch member by any suitable means and for that purpose the means disclosed in the Pope and Randall Patent No. 1,241,882 supra, and more particularly shown in Fig. 3 of said patent, is illustrated. This comprises a flat thin leaf spring 6 located in the slot 3 alongside of the shank of the latch member and provided with a lateral bend by which it serves to press the shank of the latch member into engagement with the walls of the slot 3.

120

125

130

- A projection 7 at the inner or rear end of this leaf spring enters a circumferential groove in a cap 8 mounted on the stud 2 and serves to hold the springs in position.
- 5 But it is obvious that any suitable means may be employed to give the necessary retarding action to the latch member.
- The construction of the hook and latch members is fully shown by the drawings.
- 10 The hook member comprises the usual butt 9 to co-operate with the groove in the needle operating cam, the rearwardly extending shank 10, the forwardly extending hooked end 11 and the transverse slot 12. The outer surface of the hook 11 is notched or recessed at 13 to receive the point of the latch.
- The transverse slot 12 is formed by a saw cut which leaves a shoulder 14. The surface 15 of the slot extending up toward the
- 20 hook from this shoulder is in the present invention formed by a separate operation to present a straight extended bearing surface along which the latch member slides during its movement with respect to the hook member.
- 25 The hook member is preferably formed of flat sheet metal by a punching operation during which the inner or rearward shoulder 16 in the shank is formed. If the hook member is otherwise formed then this shoulder is subsequently formed by a punching or stamping operation so that the position of this shoulder 16 with respect to the butt 9 of the hook member and particularly with
- 30 respect to the rear or driving edge of this butt is determined with great accuracy. This insures the uniform and accurate projection of the latch when the needle is receiving the yarn.
- 35 The latch member is preferably stamped or punched out of thin sheet metal at a single operation and comprises the point 17 presenting the extended straight bearing surface 18 to co-operate with the surface 15 of the hook member, the shoulder 19 to co-operate with the shoulder 14 on the hook member and the shoulder 20 to co-operate with the shoulder 16 on the hook member, and the tail 21 to ride in the
- 40 groove 3. The shoulder 20 being formed by a stamping or punching operation is also accurately related to the extreme tip or point of the latch member.
- 45 It will be seen that if the shoulder 14 were to be formed by a punching or stamping operation it would be necessary to cut through the entire body of the hook member and therefore to move the shoulder further to the rear and reduce the area of the side
- 50 surfaces of the slot 12, thus reducing those surfaces which in co-operation with the side surfaces of the latch member insure the accurate guiding of the members in transverse relation to each other and whereby the
- 55 point of the latch is accurately brought into transverse relation with the tip and hook. But as extreme accuracy of relation in the retracting movement of the members is not essential the shoulder 14 formed in the cutting of the slot 12 may be utilized.
- 60 The operation of the needle will now be apparent. During the projecting movement to bring the needle to yarn receiving position the hook member, projected by the action of the cam 5, brings the shoulder 16 into contact with the shoulder 20 on the latch member and the parts are carried along in the position shown in Fig. 3 to yarn receiving position, which position is reached with absolute accuracy by both
- 65 members. Hence when the yarn is fed it is brought directly down into or behind the hook 11. On the retracting movement the hook member is retracted first by the action of the cam 5 until the shoulder 19 on the latch member comes into contact with the shoulder 14 at which time the point 17 of the latch will rest in the recess 13 of the hook 11 enclosing the yarn just fed in the hook. As the retracting motion continues
- 70 the loop fed on the preceding stitch to the needle rides along the point of the latch and is cast off. The strain thus coming upon the latch is effectively taken up because the point of the latch is then supported on one
- 75 end in the recess of the tip of the hook and on the other end on the flat bearing surface 15, while at the same time the cross section of the needle at the casting off point is at
- 80 the minimum.
- 85 During the relative movements of the members of the needle it will be seen that the surface 18 is sliding practically throughout its travel on the surface 15 thus reducing the wear and friction. When the needle is moved forward with the shoulders 16 and 20 in contact the point of the latch also rests upon the inclined surface 15 and the latch member is prevented thereby from swinging inward and getting out of the slot in the
- 90 hook member.
- 95 It will be seen that the construction thus set forth is one which may be embodied in the needle members by simple mechanical operations rendering the needle capable of
- 100 speedy manufacture at low cost while at the same time extreme accuracy of movement and position such as is required especially in the dial needle to secure proper cooperation is secured.
- 105 The invention is shown as applied to a cylinder needle in Fig. 5 and as the construction is generally similar in all respects no detailed description is necessary.
- 110 In this construction the portion of the cylinder 22 of a knitting machine is shown provided with a slot 23 for the latch member and a superimposed wider slot 24 for the hook member. The hook member has its shank 25 extended and provided with the
- 115
- 120
- 125
- 130

usual butt 26 co-operating with the usual cam 27 while the tail 28 of the latch member is extended, but otherwise the construction of the parts is similar to that already described.

This application is restricted to the invention involving the punching construction covered by the claims. Other and independent inventions depending upon the construction of the needle independent of the punched features are made the subject of my later application No. 263,726 filed November 22, 1918.

Having fully described my invention, what I claim as new and desire to secure by Letters Patent is:

1. A separate latch knitting machine needle comprising a hook member provided with a driving edge, a latch member, and means for securing relative longitudinal bodily movements of said members to effect the co-operative action of the hook and latch, the said means comprising co-operating punched shoulders, one on the hook member accurately positioned with respect to said driving edge, and the other on the latch member accurately positioned with respect to the point of the latch, whereby upon the projection successively of the hook members of a series of said needles by their driving edges to yarn-receiving position the projected position of the latch member of each needle is accurately and uniformly secured.
2. A separate latch knitting machine needle comprising relatively, bodily, longitudinally movable hook and latch members, the hook member provided with a driving edge and a latch projecting shoulder both punched in accurate position with respect to the hook and the latch member provided with a projecting shoulder punched in ac-

curate position with respect to the point of the latch, whereby upon the projection successively of the hook members of a series of said needles by their driving edges to yarn-receiving position the projected position of the latch member of each needle is accurately and uniformly secured.

3. A series of separate latch knitting machine needles each comprising relatively bodily longitudinally movable hook and latch members, means for securing the said relative movements of the said members to effect the co-operative action of the hook and latch comprising driving shoulders one on the hook member and one on the latch member formed by a punching operation and insuring accurate and uniform projected position and relation of the members in all of the needles.

4. A knitting machine needle comprising a longitudinally slotted hook member provided with a driving edge, a separate latch member provided with a head passing through the slot of the hook member, and means for securing relative longitudinal and transverse bodily movements of said members to effect the co-operative action of the hook and latch, the said means comprising co-operating punched shoulders, one on the hook member accurately positioned with respect to said driving edge and the other on the latch member accurately positioned with respect to the point of the latch, to effect the forward or projecting movement of the latch member and insure its uniform and accurate projection to yarn-receiving position.

In testimony whereof, I have signed my name to this specification.

PATRICK P. LA MONTAGNE.
